UNITED STATES PATENT OFFICE.

ELI GADBOIS, OF CHICAGO, ILLINOIS.

DOOR-CHECK.

1,071,409.

Specification of Letters Patent. Patented Aug. 26, 1913.

Application filed February 12, 1913. Serial No. 747,870.

To all whom it may concern:

Be it known that I, ELI GADBOIS, a citizen of the United States, and a resident of the city of Chicago, county of Cook, and 5 State of Illinois, have invented certain new and useful Improvements in Door - Checks, of which the following is a specification.

My invention relates to improvements in door checks and has for its object the production of a device of this character which 10 will be of durable and economical construction and efficient in use.

Other objects will appear hereinafter.

The invention consists in the combinations 15 and arrangements of parts hereinafter described and claimed.

The invention will be best understood by reference to the accompanying drawing forming a part of this specification, and in 20 which,

Figure 1 is a front elevation of the upper end portion of a door and door casing to which is applied a door check embodying my invention, Fig. 2 is a top plan view of 25 the construction shown in Fig. 1, a portion of the door casing being broken away in order to expose underlying parts, and Fig. 3 is an enlarged detail section taken on substantially line α — α of Fig. 2.

30 The preferred form of construction as illustrated in the accompanying drawing comprises a bracket 1 the rearward or base end of which is secured rigidly to the under side of the upper rail 3' of the door casing 35

3. Mounted upon the outer end of the bracket 1 is a door check 4 of any approved design, one of the pneumatic type being preferably employed the base 2 of said check being rigidly secured to said end of said 40

bracket. Connected with the oscillatory spindle 4' of the check 4 is an outwardly projecting arm 5. Fulcrumed intermediate its extremities at 6 to the outer end of the bracket 1 is a lever 7 curved, as shown.

45 One end of the lever 7 is connected by means of a link 8 with the outer end of the arm 5, the opposite end of said link being connected by means of a link 9 with a socket member 10 which is fastened to the adjacent side 50 of the door 11 close to the hinge or pivot of the latter.

In order to afford adjustment of the links 8 and 9 so as to adapt the device for use under varying circumstances, turn buckles 12 55 are employed for coöperation with said links, as will be readily understood. Cor-

responding ends of the turn buckles 12 are split as shown for embracing balls 13 provided at the ends of the arm and lever engaged by said links. Screws 14 coöperate 60 with the split ends of said turn buckles for maintaining the same in operative engagement with the balls 13 engaged thereby. The provision of ball-and-socket joints as shown in the various points in the mechanism conduces, as will be understood to ease and smoothness in the operation of the device. The link 9 is so arranged that when the door is in closed position an acute angle 65 will be formed between the same and the adjacent end of the lever 7, or said lever will approach dead center. This being so, when the door is in closed or nearly closed position, considerable power or pressure will be required to open the door, the leverage when 70 the door is in this position being reduced to a minimum. As the door opens, however, the angle between the link 9 and said lever 7 increases with a corresponding increase in the leverage developed, and so that the force 75 required to open the door decreases as the door swings to its open position, the greatest leverage being developed when the door is in fully opened position, or with the link 9 disposed at right angles to the lever 7. 80 With this arrangement then a door will be securely held in closed position and after being started to be swung to open position, may be readily swung to fully open position, 85 and held in this position with little exertion. 90

While I have illustrated and described the preferred form of construction for carrying my invention into effect, this is capable of variation and modification without departing from the spirit of the invention. I, 95 therefore, do not wish to be limited to the precise details of construction set forth, but desire to avail myself of such variations and modifications as come within the scope of the appended claims. 100

Having described my invention what I claim as new and desire to secure by Letters Patent is:

1. In a door check, the combination with a swinging door and the casing for said door, of a bracket mounted upon and projecting from said casing, a door closing and checking device mounted upon said bracket comprising an oscillatory actuating spindle; an arm connected with and projecting 105 from said spindle; an oscillatory lever fulcrumed intermediate its ends on said 110

bracket; an operative connection between one end of said lever and the outer end of said arm; and an operative connection between the opposite end of said lever and said door, substantially as described.

2. In a door check, the combination with a swinging door and the casing for said door, of a bracket mounted on said casing, a door closing and checking device mounted upon said bracket comprising an oscillatory actuating spindle; an arm connected with and projecting from said spindle; an oscillatory lever fulcrumed intermediate its ends; a link connecting one end of said lever with the outer end of said arm; and a second link connecting the other end of said lever with said door, substantially as described.
- 10 3. In a door check, the combination with a swinging door and the casing for said

door, of a bracket mounted on said casing, a door closing and checking device mounted upon said bracket comprising an oscillatory actuating spindle; an arm connected with and projecting from said spindle; an oscillatory lever fulcrumed intermediate its extremities; a longitudinally adjustable link connecting one end of said lever with the outer end of said arm; and a second longitudinally adjustable link connecting the opposite end of said lever with said door, substantially as described. 25 30

In testimony whereof I have signed my name to this specification in the presence of two subscribing witnesses.

ELI GADBOIS.
